CLAIM

The ornamental design for a mini ball rack with three poles, as shown and described.

DESCRIPTION

FIG. 1 is a perspective view of the mini ball rack with three poles invention;

FIG. 2 is a front view thereof;

FIG. 3 is a top view thereof;

FIG. 4 is a right end view, the left end view forming a mirror image of said right side and thus is not shown;

FIG. 5 is a bottom view; and,

FIG. 6 is a back view thereof.

1 Claim, 3 Drawing Sheets
